Patented Oct. 19, 1976

241,893

COMBINED TABLE AND MULTIPLE SEATING UNIT

Mirko Cavic, 293 Paxton St., Paterson, N.J. 07503

Filed Aug. 26, 1974, Ser. No. 500,587

Term of patent 14 years

Int. Cl. D6—05

U.S. Cl. D6—45

FIG. 1

FIG. 2

FIG. 3

FIG. 4

FIG. 5

FIG. 1 is a side view of my invention, the opposite side being the same as shown in FIG. 1;

FIG. 2 is an end view of the invention of FIG. 1, the opposite side being the same as FIG. 2;

FIG. 3 is a top view of the invention of FIG. 1;

FIG. 4 is a bottom view of the invention of FIG. 1; and

FIG. 5 is a perspective view of the invention of FIG. 1.

I claim:

The ornamental design for a combined table and multiple seating unit, as shown and described.
